WEAVING FRAMES

Louis H. Morin, Bronx, N. Y., assignor to Coats & Clark, Inc., New York, N. Y., a corporation of Delaware

Application April 5, 1954, Serial No. 420,999

8 Claims. (Cl. 28—15)

This invention relates to what are generally referred to as weaving frames. More particularly, the invention deals with a frame structure composed of four identical rail parts with interengaging means at end portions of said parts for adjustably clamping one end of one part with the opposed end of another part in adjustment of the frame to predetermined dimensions.

Still more particularly, the invention deals with a frame, wherein the separate parts of each of the rails are formed from die castings, mouldings and extruded products which can be quickly and easily assembled in forming the rail assemblage.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a perspective view of one corner portion of a weaving frame made according to my invention, with parts of the construction broken away.

Fig. 2 is a broken sectional and plan view showing two corner portions of a frame and illustrating parts of three rails of a frame.

Fig. 3 is an edge view of one corner portion of a frame made according to my invention; and

Fig. 4 is a view looking in the direction of the arrow 4 of Fig. 3, omitting the winged screw and also omitting parts of the background showing.

My invention deals with weaving frames composed of four adjustably coupled members to facilitate formation of rectangular frames of different areas, depending upon the weaving operation to be performed. In order to simplify the showing, portions of three of the members employed are indicated in Fig. 2 of the drawing. It will be apparent, however, that the fourth member is identical with the three members which are partially shown. As all of the members are of identical construction, the brief description of one member will be applicable to all.

In Fig. 2 of the drawing, 10 represents a plan view of one end portion of a frame member. 10' indicates part of a similar member, coupled with the end portion of the member 10. 10'' represents a portion of a third member, similar to the member 10, and no showing is made of the fourth member. Where identical parts of the members are shown in the views, the reference numerals will be primed consistent with the priming of said members.

Each member comprises an elongated and preferably extruded rail 11 substantially of L-shaped cross-sectional form, note Fig. 3. The rail 11 is defined by angularly disposed wall portions 12 and 13, the free edge of the wall portion 13 terminating in an angularly extending flange 14. The upper surface of the wall 12 has an elongated dovetailed channel or recess 15 extending the full length of said wall or, in other words, opening through both ends of the rail.

A die cast bracket 16 is fixed to one end of the rail 11, the bracket comprising a substantially V or yoke-shaped

2

channel portion defined by walls 17, 18 and 19, the walls 17 and 18 being disposed at right angles to each other; whereas, the wall 19 flares upwardly and outwardly a sufficient degree to freely receive the rail 11, as clearly noted in Fig. 3 of the drawing.

Extending outwardly from the wall 19 is a cylindrical portion 20 which is internally threaded to receive the winged set or clamp screw 21, the screw 21 having a winged fingerpiece end portion 22. Extending from the wall 17, adjacent one edge thereof and at right angles to said wall, is a plate portion 23 having integral rivet portions 24 on the surface thereof. The rivet portions 24 are adapted to pass through corresponding apertures formed in the end 25 of the rail or in the wall 13 of said end and to be headed over, as seen at 26, in securely fixing the bracket 16 to the end 25 of the rail. For purposes of description, the end 25 of the rail can be defined as the bracket end of the rail; whereas the opposed end can be regarded as the free end.

15 The bracket 16 also includes a reinforcing rib 27 which is in alignment with the plate 23 and extends beneath the wall 18 and onto the cylindrical portion 20, as clearly seen in Figs. 3 and 4 of the drawing. The cylindrical portion 20 also includes an upwardly contracted marker or indicator 28 to gauge adjustment of the members one with respect to the other in regulating the size of the frame to be formed.

20 The screw 21 can be formed as a die cast product, thus simplifying the cost of production of the resulting frame. 30 However, other types of screws can be used, if desired. In considering Figs. 1 and 3 of the drawing, it will be apparent that the screw 21 operates to engage the wall 13' of the rail 11' in securely clamping the rail 11' in the yoke-shaped portion of the bracket 16 in adjusting the 35 size of the resulting frame.

I also employ pin strips 29 which constitute part of each of the rails and, here again, the pin strips are all of similar construction, thus making each rail identical in construction with the companion rails. The strip 29 is 40 preferably formed as a moulded plastic product and comprises a baseplate portion 30 of dovetailed cross-sectional form to fit snugly in the dovetailed recess or channel 15 of the rail 11, as is clearly illustrated in Fig. 3 of the drawing. The strip has, spaced along the upper surface 45 thereof and protruding above said surface, a predetermined common spacing of pin members 31, the pin members in the construction shown being in the form of a relatively thin but wide members, as clearly illustrated in Figs. 1, 2 and 3 of the drawing, and these members being 50 preferably disposed adjacent the edge portion 32 of the baseplate 30 and the pin members taper upwardly, in the manner clearly noted in Figs. 2 and 3 of the drawing. The pin members 31 have outer edges 33 and inner edges 34.

55 Considering Fig. 3, it will be apparent that the outer edge 33' of the pin members 31' are disposed at right angles to or perpendicularly to the baseplate 30'; whereas the inner edge 34' is tapered upwardly and inwardly so that the upper ends of the pin members are of less width than the lower end portions thereof. This construction facilitates attachment and detachment of the yarns from the frame in the use thereof. Spaced along the upper surface of the baseplate 30 are numerals, parts of which are seen at 35', the numerals "17" and "18" being diagrammatically shown in Fig. 1 of the drawing; whereas the numeral "1" is indicated at 35 in Fig. 2 of the drawing. In the construction shown, these numerals would indicate substantially eighteen inches of length in the pin strips 29, 29' employed.

60 At widely spaced intervals along the outer edges of the baseplate are key notches. To illustrate at least one of these notches, the bevelled edge 36' of the baseplate

30' has a key notch 37', into which part of the wall portion 12' is pressed in definitely keying the pin strip 29' in proper position on the rail 11'. The notch 37' is indicated in Fig. 1 of the drawing, but several of these notches are employed on the pin strip 29' and on all of the pin strips employed.

It will be apparent from a consideration of Fig. 2 of the drawing that the free end of each rail is adjustable through the bracket end of an associated rail and can be clamped with the associated rail by the set or clamp screw. In Fig. 2 of the drawing, the screw 21 is shown engaging the rail 11' and the screw 21' is shown engaging the rail 11''. In shipment and storage of the frame, it will be apparent that the rails can all be disassembled and packed or stored in a relatively compact elongated package.

For purposes of description, the wall 12 of the rail 11 can be regarded as the top wall, the wall 13 as the inner wall and, correspondingly, the wall 17 of the bracket 16 can be regarded as a back wall, the wall 18 as a bottom wall and the wall 19 as a front wall. In this connection, it is to be noted that the baseplate 30 of the pin strip 29 has its upper surface flush with the upper surface of the top wall 12 of the rail. The pins or pin members 31, accordingly, may be said to be adjacent the inner or rear edge of the strip; whereas, the numerals 35 are disposed at the outer edge thereof. While reference here is made to the parts only of the member 10, the same is, of course, applicable to the other members of the frame employed, as for example, the members 10' and 10''.

Having fully described my invention, what I claim as new and desire to secure by Letters Patent is:

1. A weaving frame comprising four similar detachably and adjustably coupled members, each member comprising an elongated rail substantially L-shaped in cross-sectional form, said rail being defined by angularly disposed walls, one wall having a longitudinal dovetailed groove opening through a side surface thereof, the other wall terminating at its free edge in an angularly extending flange, a bracket fixed to one end of the rail, the bracket including a substantially V-shaped channel portion for reception of a companion rail in adjustment of the rails one with respect to the other, the said other wall of the L of a rail having one of its faces abutting one side of the said channel portion of one of the said brackets, manually actuated means on said bracket operatively engaging the opposite face of said other wall between the first-mentioned wall and said angularly extending flange, a pin strip mounted in the groove of said rail, said pin strip comprising a baseplate, and a plurality of pin members projecting from the baseplate and spaced longitudinally of said strip.

2. A weaving frame comprising four similar detachably and adjustably coupled members, each member comprising an elongated rail substantially L-shaped in cross-sectional form, said rail being defined by angularly disposed walls, one wall having a longitudinal dovetailed groove opening through a side surface thereof, the other wall terminating at its free edge in an angularly extending flange, a bracket fixed to one end of the rail, the bracket including a substantially V-shaped channel portion for reception of a companion rail in adjustment of the rails one with respect to the other, the said other wall of the L of a rail having one of its faces abutting one side of the said channel portion of one of the said brackets, manually actuated means on said bracket operatively engaging the opposite face of said other wall between the first-mentioned wall and said angularly extending flange, a pin strip mounted in the groove of said rail, said pin strip comprising a baseplate, a plurality of pin members projecting from the baseplate and spaced longitudinally of said strip, and said manually actuated means comprising a screw having a winged fingerpiece portion.

3. A weaving frame comprising four similar detachably and adjustably coupled members, each member com-

prising an elongated rail substantially L-shaped in cross-sectional form, said rail being defined by angularly disposed walls, one wall having a longitudinal dovetailed groove opening through a side surface thereof, the other wall terminating at its free edge in an angularly extending flange, a bracket fixed to one end of the rail, the bracket including a substantially V-shaped channel portion for reception of a companion rail in adjustment of the rails one with respect to the other, manually actuated means on said bracket operatively engaging a rail disposed in the channel of the bracket in securing the rail within the channel of said bracket, a pin strip mounted in the groove of said rail, said pin strip comprising a baseplate, a plurality of pin members projecting from the baseplate and spaced longitudinally of said strip, said manually actuated means comprising a screw having a winged fingerpiece portion, and said bracket and pin strip having cooperating means guiding adjustment of the rails one with respect to the other.

4. A weaving frame comprising four similar detachably and adjustably coupled members, each member comprising an elongated rail substantially L-shaped in cross-sectional form, said rail being defined by angularly disposed walls, one wall having a longitudinal dovetailed groove opening through a side surface thereof, the other wall terminating at its free edge in an angularly extending flange, a bracket fixed to one end of the rail, the bracket including a substantially V-shaped channel portion for reception of a companion rail in adjustment of the rails one with respect to the other, manually actuated means on said bracket operatively engaging a rail disposed in the channel of the bracket in securing the rail within the channel of said bracket, a pin strip mounted in the groove of said rail, said pin strip comprising a baseplate, a plurality of pin members projecting from the baseplate and spaced longitudinally of said strip, said manually actuated means comprising a screw having a winged fingerpiece portion, said bracket and pin strip having cooperating means guiding adjustment of the rails one with respect to the other, said last named means comprising numerals on said strip, and a projection on said bracket.

5. A weaving frame comprising four similar detachably and adjustably coupled members, each member comprising an elongated rail substantially L-shaped in cross-sectional form, said rail being defined by angularly disposed walls, one wall having a longitudinal dovetailed groove opening through a side surface thereof, the other wall terminating at its free edge in an angularly extending flange, a bracket fixed to one end of the rail, the bracket including a substantially V-shaped channel portion for reception of a companion rail in adjustment of the rails one with respect to the other, the said other wall of the L of a rail having one of its faces abutting one side of the said channel portion of one of the said brackets, manually actuated means on said bracket operatively engaging the opposite face of said other wall between the first-mentioned wall and said angularly extending flange, a pin strip mounted in the groove of said rail, said pin strip comprising a baseplate, a plurality of pin members projecting from the baseplate and spaced longitudinally of said strip, and the pins of said strip comprising transversely wide and outwardly tapered members.

6. A weaving frame comprising a plurality of similar members, each member comprising an elongated rail L-shaped in cross-sectional form, said rail being defined by angularly disposed top and inner walls, the top wall having, on its outer surface, a longitudinal groove of dovetailed cross-sectional form, a pin strip fixed in said groove and having upwardly extending longitudinally spaced pin members, a bracket fixed to one end of each rail, said bracket having a substantially V-shaped channel portion for reception of a companion rail, said channel portion being defined by angularly arranged inner, bottom and front walls, the front wall of said bracket including an

internally threaded cylindrical portion, a winged screw adjustably mounted in said cylindrical portion and extending into the channel of the bracket to operatively engage the inner wall of an associated rail in adjustably coupling a pair of rails together, said pin strip having gauge markings extending longitudinally thereof, and the cylindrical portion of said bracket having a projection adapted to register with the markings of said strip.

7. A weaving frame comprising a plurality of similar members, each member comprising an elongated rail L-shaped in cross-sectional form, said rail being defined by angularly disposed top and inner walls, the top wall having, on its outer surface, a longitudinal groove of dovetailed cross-sectional form, a pin strip fixed in said groove and having upwardly extending longitudinally spaced pin members, a bracket fixed to one end of each rail, said bracket having a substantially V-shaped channel portion for reception of a companion rail, said channel portion being defined by angularly arranged inner, bottom and front walls, manually actuated means mounted in the front wall of the bracket and operatively engaging the inner walls of a rail disposed in the channel of the bracket in adjustably coupling the bracket end of one rail with the companion rail, said strip comprising a dovetailed baseplate arranged in the groove of the top wall of said rail, the upper surface of the baseplate being in alignment with the corresponding surface of said top wall, said

pins being arranged adjacent the inner edge portion of said strip, and said pins being transversely wide and upwardly tapered.

8. In weaving frames employing four detachably and adjustably coupled rails, with means at one end of each rail for clamping an associated rail therewith, each rail including a one-piece plastic pin strip comprising an elongated baseplate having inner and outer edge portions, a plurality of integral transversely wide pin members spaced along and projecting from the inner edge portion of said strip, said pin members tapering outwardly with respect to said baseplate, outer edge portions of the pin members being disposed at right angles to the upper surface of the baseplate, and inner edge portions of said pin members tapering outwardly to provide outer ends on the pin members which are narrower than the base of said pin members.
